[57] CLAIM

The ornamental design for a pet ball scoop handle, as shown and described.

DESCRIPTION

FIG. 1 is a side, top perspective view of the pet ball scoop handle. The broken line showing of the scoop is for illustrative purposes only and forms no part of the claimed design.

FIG. 2 is a top view thereof;
FIG. 3 is a bottom view thereof;
FIG. 4 is a front view thereof;
FIG. 5 is a left side view thereof; and,
FIG. 6 is a right side view thereof.
